LIGHT METER

Roger B. Kerr, Jamestown, R. I., and Frank
Gianascol, Lynn, Mass., assignors to General
Electric Company, a corporation of New York

Application September 4, 1952, Serial No. 21,302

Term of patent 14 years

(Cl. D61—1)

To all whom it may concern:

Be it known that we, Roger B. Kerr and Frank
Gianascol, citizens of the United States, residing,
respectively, at Jamestown, in the county of
Newport, State of Rhode Island, and at Lynn, in
the county of Essex, State of Massachusetts, have
invented a new, original, and ornamental Design
for a Light Meter, of which the following is
a specification, reference being had to the accom-
panying drawing, forming a part thereof.

Fig. 1 is a front elevational view of a light meter
showing our new design;

Fig. 2 is a side elevational view; and

Fig. 3 is an end view thereof.

We claim:

The ornamental design for a light meter, sub-
stantially as shown.

ROGER B. KERR.
FRANK GIANASCOL.
